ABSTRACT OF THE DISCLOSURE

The sounder in a toy gun is actuated by an inertia motor driven through a gear train by a toothed portion of a reciprocating trigger. Elements of the gear train disengage when the trigger is not pulled back. A driven cam on one of the gears of the train engages a reciprocating clapper hammer pivotally mounted within the housing of the toy gun. Both the trigger and the reciprocating hammer are biased to idle positions by integrally formed cantilever leaf springs unitarily molded with the respective elements.

BACKGROUND OF INVENTION

(1) Field of invention

The present invention generally deals with a percussion noisemaker toy.

(2) Description of the prior art

Previous known percussion toys have had pivotally mounted reciprocating components. However, these components, whatever their function, have had separate spring biasing means for returning them to idle positions. In some devices, the biasing spring would be a torsion spring concentrically mounted about the same pivot as the reciprocating component and biased between an abutment on the frame of the toy and an abutment on the reciprocating component. Other known biasing means included a coil tension spring stretched between abutments on both the frame and the reciprocating component. Problems encountered with the previously known devices included the high costs of assembly of the many parts with separate spring elements. An assembler in a production line would have to manually insert each spring and connect each end to its appropriate position. In many instances the springs would be relatively small and the assembly process would thus entail considerable time and expense.

A still further drawback of present construction methods is the tendency of the springs to unseat themselves as partly assembled frame sections are aligned and fastened together.

Still another disadvantage is the tendency for the elements to unseat themselves during operation of the toy. As the number of the moving components increases so does the likelihood of failure of the toy due to the failure of a single component.

SUMMARY OF THE INVENTION

It is an object of the present invention to provide a toy having reciprocating spring biased components so constructed that they are not subject to any of the foregoing disadvantages.

More specifically, it is an object of the invention to provide a toy of the character described which is simple and rugged in construction and can be easily fabricated by mass production methods.

It is another object of the invention to provide a toy of the character described wherein a pivotally mounted reciprocating element is biased to an idle position by a resilient leaf spring integrally formed with the element

so that the parts may be simply assembled without the necessity of positioning separate springs.

It is another object of the invention to provide a toy gun of the character described wherein a molded percussion clapper hammer is biased by such an integral leaf spring unitarily molded with the hammer.

It is another object of the invention to provide a toy gun of the character described wherein a molded pivotally mounted trigger plate is biased by such an integral leaf spring unitarily molded with the plate.

Other objects of the invention in part will be obvious and in part will be pointed out hereinafter.

The invention accordingly consists in the features of construction, combinations of elements and arrangements of parts which will be exemplified in the toy gun herein-after described and of which the scope of application will be indicated in the appended claims.

In general the invention is carried out by molding the element to be biased of an elastomeric plastic in one piece with a unitary leaf spring. The element is made thick enough to be stiff while the spring is made thin enough to be resilient. Preferably the spring is of hairpin shape to obtain maximum distribution of stress and at least one end of the spring is joined to the element.

BRIEF DESCRIPTION OF THE DRAWINGS

In the accompanying drawings in which is shown one of the various possible embodiments of the invention:

FIG. 1 is an isometric view of a toy gun constructed in accordance with and embodying the present invention;

FIG. 2 is an enlarged fragmentary view taken substantially along the line 2—2 of FIG. 1 and showing in dot and dash lines a second position assumed by the trigger plate;

FIG. 3 is a sectional view taken substantially along the line 3—3 of FIG. 2;

FIG. 4 is a sectional view taken along the line 4—4 of FIG. 2 and showing the hammer mechanism prior to release; and

FIG. 5 is a view showing in detail an alternate embodiment of the trigger plate mechanism, on a reduced scale.

DESCRIPTION OF THE PREFERRED EMBODIMENT

Referring now in detail to the drawings, the reference numeral 10 denotes a toy gun which embodies the present invention. Said gun is composed of two outer shell halves 12 and 14 secured together at their peripheral flanged edges 16 by any suitable means such as an adhesive or a heat seal. Integrally formed with the contour of the shell are two hand grips 18, 20, a barrel 21, a gun stock 22, a trigger section 24 and a sound chamber 26, the latter simulating a cartridge clip receiver.

A trigger plate 28 has unitary trunnions 30, 32 rotatably supported in bearings 34, 36 for rocking movement of the plate 28 in an arc. The bearings are molded as parts of the shell halves and are located within the hollow interior of the gun defined by the shell. Abutment shoulders 38, 40 prevent lateral displacement of the trigger plate 28. A finger trigger portion 42 depends through a trigger guard opening 44 in the peripheral edges 16 for movement between a forward abutment stop 46 and a rear abutment stop 48. The forward edge of trigger plate 28 contains an arcuate toothed rack sector 50.

Pursuant to the present invention, rearwardly of the rack sector 50 a cantilever leaf spring elongated biasing element 52 of oblong cross-section projects upwardly from a juncture point with the body of the trigger plate 28 in back of the trunnions 30, 32. The biasing element 52 has a retroverted bend 54 formed at its upper right portion presenting an inverted U configuration. Biasing element 52 biases the trigger plate 28 in a clockwise direc-

tion as viewed in FIG. 2 so that when the trigger plate is idle (not pulled back by an operator's finger) the finger portion 42 rests against the forward stop 46 as shown in the dot-and-dash lines of FIG. 2. The rear edge 56 of the downwardly extending leg 57 of the biasing element 52 maintains engagement with an abutment post 58 molded with the shell half 14 located within the gun to provide sufficient clockwise biasing force throughout the movement of the trigger plate 28 between the limits of rotation as defined by the stops 46 and 48.

The trigger plate 28 with its biasing element 52 is unitarily molded of any suitable synthetic elastomeric plastic such as a butadiene (15%) modified polystyrene (85%), polypropylene, polyethylene or polyvinyl chloride, for example. The plate is made sufficiently thick, e.g. nine-hundredths of an inch and is provided with peripheral stiffening flanges having, for example, a width of fifteen-hundredths of an inch and a breadth of one-tenth of an inch, so that the plate is stiff, that is to say, not noticeably resilient under the pressures applied in operation. Likewise the trigger portion is made sufficiently heavy to be essentially inflexible in use. However, the leaf spring is made sufficiently thin, e.g. six-hundredths of an inch in the direction of flexure and without stiffening flanges so that it is resilient. The provision of the retroverted bend 54 between the area of contact 56 with the fixed abutment 58 and the body of the trigger plate 28 is preferred in order to avoid the possibility of having the cantilever element take on a permanent set in its biased (stressed) position and thus reduce the spring efficiency.

It has been found that unitarily molded straight cantilever leaf spring elements are prone to acquire a permanent set after a period of continued usage. Optimum results were obtainable with the retroverted bend being positioned intermediate the ends of the leaf spring and thus the preferred embodiment is illustrative of such configuration. In idle (forward) position of the trigger portion the biasing element is under stress forcing the said portion against the stop 46.

An alternate embodiment of the trigger plate is illustrated in FIG. 5. In this embodiment the trigger plate 28a is substantially identical to trigger plate 28 except that the leaf spring element 52a forms a closed loop. Two retroverted bends 54a and 54b join the opposite ends of the rearward edge 56a of the leaf element to the juncture points with the body of the trigger plate. The trigger plate 28a and spring element are also unitarily molded of any suitable elastomeric synthetic plastic and said plate is interchangeable with the trigger plate 28.

Concentric idler gears 60 and 62 are unitarily joined and are fixedly mounted on trunnions 64 which in turn are slidably and rotatably received within supporting bearings 66 in the halves 12 and 14 for translational movement along a sloping arcuate path 63 defined by the extreme positions shown in the solid and dot-and-dash lines of FIG. 2, said path being concentric with the arcuate rack sector 50 of the trigger plate 28.

Concentric driven gears 68 and 70 are unitarily joined and are fixedly mounted on trunnions 72 which in turn are rotatably supported within bearings 74 in the halves 12, 14.

A gear 78 is mounted on trunnions 82 and is unitary with a heavy inertia wheel 80. The trunnions are journaled within bearings 84. The gear 78 continually engages gear 70 in intermeshing relationship. The gear 68 engages the gear 62. The rack gear sector 50, and the chain of gears 60, 62, 68, 70 and 78, constitute a gear reduction train for spinning the inertia wheel 80 which acts as an inertia motor so long as it turns.

When the finger portion 42 is moved from the forward dot-and-dash line position to the rearward solid line position against the restoring biasing tongue of the cantilever biasing element 52, the rack 50 engaging the gear 60 causes the gears 60 and 62 to rotate clockwise as

viewed in FIG. 2 and simultaneously rack 50 exerts a pressure maintaining the trunnions 64 at their lowermost position within the arcuate path 63. The gear 62 engaging the gear 68 causes the gears 68 and 70 to rotate counterclockwise (as viewed in FIG. 2). The gear 70 in engagement with the gear 78 will thus initially drive the gear 78 and the inertia wheel 80.

When the trigger finger portion 42 reaches the rearward stop 48, the gears 60 and 62 will continue to rotate due to inertia and will climb upwardly along to the top of the rack 50 and the bearing 66 to a stop defined by the limits of path 63 within the bearing 66. Thus the gear 62 will disengage from the gear 68 thereby allowing the gear 68 and the inertia wheel to continue spinning.

When manual pressure on the trigger finger portion 42 is released, the biasing element 52 will urge the trigger plate 28 in a clockwise direction (as viewed in FIG. 2) about the bearings 34 and 36. When the trigger plate 28 reaches its maximum clockwise position, the idler gears 60 and 62 will remain in their uppermost position as defined by the dot-and-dash lines of FIG. 2 as there is sufficient frictional resistance between the bearings 66 and the trunnions 64 to prevent the idler gear 62 from reengaging the gear 68 under gravitational force alone.

When the finger element 42 is again manually pressed, the rack 50 engaging the gear 60 urges it to its lowermost position and into engagement with the gear 68.

Thus, a single pull of finger element 42 will cause the gears 68 and 70 to rotate in a counterclockwise direction until the rotational energy stored in the inertia wheel 80 has been fully dissipated and repeated pulls of the finger element will both cause further driven rotation of the gears 68 and 70 and also maintain and increase rotational energy in the inertia wheel 80 insuring uninterrupted rotation of the gears 68 and 70. This type of actuation of the gear train and inertia wheel is well known in the art and therefore will not be further detailed.

On the back face 86 of the gear 70 (FIG. 4) edge 40 cams 88 and 90 are positioned. These cams present two arcuate wedge shaped edges concentric with the gear 70 and gradually sloping from surfaces flush with the face 86 to sharp drops.

A clapper 91 is located within the shell halves 12 and 14 within the sounding chamber 26. The clapper 91 consists of an elongate body mounted by trunnions 92 and rotatably supported in slots 94 forming bearings 96. Bearings 96 project from the side wall of the shell section 14. Mating flat abutment members project from the opposite side wall of shell section 12 to encase the trunnions 92 within the slots 94. Abutment shoulders 98 prevent lateral displacement of the clapper hammer 91 during operation. At the lower end of the clapper body is a hammer portion 100 constructed to strike the side wall 102 of the sounding chamber 26. The upper end of the clapper body consists of a cam follower 103 designed to engage the edges of the cams 88 and 90.

Pursuant to the instant invention, a cantilever leaf spring elongated biasing element 104 projects upwardly from the body of the clapper hammer 91. The biasing element 104 is formed with a retroverted bend 106 at its upper bight portion, presenting an inverted U configuration. The rearward edge 108 of the downwardly extending leg of the biasing element 104 maintains engagement with an abutment 110 formed in the shall half 12 to provide a biasing force urging the clapper body in a clockwise direction as viewed in FIG. 4. The force provided will thus urge the cam follower 102 against the edges of the cams and likewise urge the hammer portion 100 toward the side wall 102.

The clapper hammer 91 with its biasing element 104 is unitarily molded of any suitable synthetic elastomeric plastic such as the one of which the trigger plate 28 is molded, the retroverted bend 106 serving the same function as that in the trigger plate biasing element 52.

The body of the clapper hammer including the follower 103 is made thick enough, e.g. nine-hundredths of an inch thick and two-tenths of an inch wide, to ensure operational stiffness thereof despite the fact that the hammer is made from an elastomeric plastic. However, the leaf spring is made sufficiently thin, e.g., six-hundredths of an inch, to be resilient and thereby enable it to act as a spring. Both spring elements 52, 104 are essentially hairpin springs which store up energy by having their legs relatively moved together so as to both flex the legs and the retroverted bends, thereby distributing the stress sufficiently to eliminate any tendency to assume a permanently deformed set under stress.

As the rear face 86 of the gear 70 turns, the cam follower 102 will move the clapper hammer 91 in a counterclockwise direction as viewed in FIG. 4 against the bias of the spring element 104 until the follower reaches the drops at which point the biasing element is free to sharply and forcibly rotate the clapper hammer in a clockwise direction causing its hammer head 100 to strike the side wall 102 and produce a loud retort.

Thus, by either a single or repeated pulls of the trigger finger element 42, the gears 68 and 70 are caused to rotate in a counterclockwise direction powered by both the trigger plate 28 and/or the inertia wheel 80. As the gears 68 and 70 rotate, the edge cams 88 and 90 engage the clapper follower 103 through each successive half revolution causing the clapper hammer head 100 to strike the side wall 102 twice for every single revolution and thus produce a machine gun like sound. It will be understood that except for the specific construction of the biasing means, the construction and operation of the sounding means is conventional.

It will be seen that there has been provided a toy having reciprocating components which achieve the various objects of the invention and which are well adapted to meet the conditions of practical use.

As various possible embodiments might be made of the above invention and as various changes might be made in the embodiments above set forth, it is to be understood that all matter herein described or shown in the accompanying drawings is to be interpreted as illustrative and not in a limiting sense.

Having thus described the present invention, there is claimed as new and desired to be secured by Letters Patent:

1. A toy having a shell defining the outer configuration thereof, a member constituting in a single molded piece of a synthetic elastomeric plastic a mechanical actuator and an elongate projection, said actuator being thicker than said projection such that said actuator is stiff and said projection is resilient, said actuator being at least partially situated in said shell, an abutment situated within said shell, means mounting said actuator to said

shell for reciprocating movement between an idle and a retracted position, said projection having one end unitarily joined with said actuator and the other end of said projection being free, said projection constituting a cantilever leaf spring biasing means, said elongate projection contacting said abutment at a point distant from said point of juncture, said elongate projection having a retroverted bend between said point of juncture and said contacting point, said elongate projection urging said actuator toward said idle position.

2. The toy of claim 1 wherein the means mounting said actuator comprises pivot supports.

3. The toy of claim 1 further including stop members, means mounting said stop members to said shell, the limits of said reciprocating movement being predetermined by said stop members.

4. The toy of claim 1 wherein said toy is a simulated firearm and said actuator is a hammer.

5. The toy of claim 1 wherein said toy is a simulated firearm and said actuator is a trigger.

6. The toy of claim 1 further including a second member constituting in a single molded piece of a synthetic elastomeric plastic a second mechanical actuator and a second elongate projection, said second actuator being thicker than said second projection such that said second actuator is stiff and said second projection is resilient, said second actuator being mounted within said shell for movement between an idle and a retracted position, said second projection having one end unitarily joined with said second actuator and the other end of said second projection being free, said second projection constituting a cantilever leaf spring biasing means, a second abutment situated within said shell, said second projection contacting said second abutment at a point distant from the point of juncture of the second projection with the second actuator to urge said second actuator toward said idle position of said second actuator, said second projection having a retroverted bend between its point of juncture with said second actuator and said second-named contacting point.

7. The toy of claim 6 wherein said toy is a simulated firearm, one of said reciprocating actuators being a hammer and the other of said reciprocating actuators being operable to drive said hammer.

8. The toy of claim 1 wherein said abutment maintains a fixed position within said shell.
